US00D877781S

(12) **United States Design Patent** (10) Patent No.: **US D877,781 S**
(45) Date of Patent: **** Mar. 10, 2020**

(54) **DISK BLADE**

(71) Applicant: **DEERE & COMPANY**, Moline, IL (US)

(72) Inventors: **Jarrod R. Ruckle**, Bondurant, IA (US); **Shawn J. Becker**, Centralia, KS (US); **David L. Steinlage**, Centralia, KS (US)

(73) Assignee: **DEERE & COMPANY**, Moline, IL (US)

(**) Term: **15 Years**

(21) Appl. No.: **29/696,380**

(22) Filed: **Jun. 27, 2019**

Related U.S. Application Data

(63) Continuation of application No. 15/945,837, filed on Apr. 5, 2018.

(57) **CLAIM**

The ornamental design for a disk blade, as shown and described.

DESCRIPTION

FIG. 1 is a front, perspective view of a disk blade shown according to the present design;

FIG. 2 is a rear, perspective view thereof;

FIG. 3. is a front view thereof;

FIG. 4 is a rear view thereof;

FIG. 5 is a side elevational view thereof; and,

FIG. 6 is a cross-sectional view thereof taken along line 6-6 in FIG. 3.

The broken line representations in the figures show unclaimed environment or boundaries. The broken line representations thus form no part of the claimed design as filed.

1 Claim, 6 Drawing Sheets
